UNITED STATES PATENT OFFICE

167,546

HAND SLED

Louis Vavrik, Rossford, Ohio, assignor to Kalamazoo Sled Company, Kalamazoo, Mich., a corporation of Michigan

Application January 24, 1952, Serial No. 18,186

Term of patent 14 years

(Cl. D34—15)

To all whom it may concern:

Be it known that I, Louis Vavrik, a citizen of the United States, residing at Rossford, in the county of Wood, and State of Ohio, have invented a new, original, and ornamental Design for Hand Sled, of which the following is a specification, reference being had to the accompanying drawing, forming part thereof.

Fig. 1 is a side elevational view; and

Fig. 2 is a plan view of a hand sled, showing my new design.

I claim:

The ornamental design for a hand sled, as shown.

LOUIS VAVRIK.
